UNITED STATES PATENT OFFICE.

ALFRED H. SMITH, OF CHAPPAQUA, NEW YORK.

RAILWAY CAR.

Application filed April 28, 1921. Serial No. 465,344.

To all whom it may concern:

Be it known that I, ALFRED H. SMITH, a citizen of the United States, residing at Chappaqua, in the county of Westchester 5 and State of New York, have invented certain new and useful Improvements in Railway Cars, of which the following is a specification.

The object of my invention is to construct 10 in a railway car specially adapted and designed to transport freight containers which containers are removably mounted and detachably secured to the car.

A further object of my invention is to 15 provide means whereby the containers may be centered and properly positioned on the car, and whereby one container may be removed from the car without disturbing the other containers on the car, or in any way 20 reducing the stability of the position of the remaining containers upon the car; and with these and other objects in view my invention consists of the parts and combination of parts as will be hereinafter more 25 fully set forth.

In the drawing—

Figure 1 is a top plan view of the car embodying my invention, said car being broken away and two freight containers 30 mounted on the car.

Figure 2 is a side elevation of the car embodying my invention with two freight containers thereon.

Figure 3 is an end elevation looking at 35 the right hand end of Figure 1.

Figure 4 is an enlarged detail sectional view on line 4—4 of Figure 3 showing the interlocking mechanism positioned near the top of the containers.

The car is composed of a skeleton frame 40 including side sills 1, end sills 2, center sills 3, bolsters 4, and needle beams 5.

Broad flat plates 6 are secured above the top edge of the center sills and smaller 45 plates 7 are secured above the top edges of the bolsters and needle beams, whereby a materially enlarged bearing surface is provided for the containers. The spaces between the side sills, bolsters and needle 50 beams are filled in with reticulated material, preferably expanded metal 8, whereby the danger of the operator falling through the bottom of the car when the car is empty is eliminated.

All side sills of the car are of skeleton form and consist of the band of wall portion 9

secured to the side sills and supported by and secured to the side stake members 10; said side stake members being formed of flat plate which is strengthened by a corrugation 11 extending vertically thereof. An angle iron 12 is secured to the top of the side stakes 10 thereby completing the side and end walls of the car.

Secured to the inner face of the side walls 65 of the car are guide and stabilizing elements 13, which are disposed at predetermined intervals throughout the length of the car and are riveted to the side stakes, the band 9 and the angle iron 12.

14 are rests or supports upon which the bottom of the containers rest. These supports are arranged on the sills, needle beams, etc., as shown in Figure 1.

At each end of the car I secure on the 75 plate 6 a two way guide and centering post 15, and at intermediate points between the ends of the car I securely position four-way guide posts 16, which guide and center the adjacent corners of four adjacent containers, 80 the containers being designated by reference numerals 17, which containers are provided with suitable doors 18, which doors, when the containers are loaded on the car, project below the angle iron 12 of the car wall 85 as shown in Figure 2, whereby the door of the container cannot be opened while the container is on the car because the side wall structure of the car functions as an abutment to prevent the opening of the door 90 while the container is on the car.

The containers are each provided with stabilizing members 19, which are adapted to function with the stabilizing elements 13 secured to the car, whereby the container 95 is held against shifting while on the car, the guide posts 15 and 16 co-acting with the stabilizing elements 13 and 19 to prevent shifting of the containers while on the car.

Near the top of each container I secure a female member 20 and a male member 21 of a locking device and similar complementary members to the top of another compartment so that when the compartments 105 are arranged in position on the car, as shown in Figure 1, these locking elements 20 and 21 engage with each other thereby locking the compartments together at the top. These locking elements 20 and 21 are shown on 110 an enlarged scale in Figure 4.

The guide posts 15 and 16 have base

flanges, as shown in the drawings while the posts extend upwardly between the compartments, as more clearly shown in Figure 3.

The compartments are provided with suitable rigidifying elements 22 and with hooks 23 which are adapted to be engaged by the lifting crane whereby the compartments may be loaded on to and unloaded from the car.

10 The car frame may include rigidifying means 24, gusset plates 25 and such other rigidifying means as may be desired by the builder.

Changes may be made in the details of 15 construction without departing from the scope of the appended claims.

What I claim is:

1. In a railway car, a frame including side sills, bolsters and needle beams, side and 20 end walls, secured to said sills in combination with a series of laden compartments adapted to be mounted upon said car within said side and end walls, co-operating guides on the compartments and side walls adapted 25 to inter-engage when the compartments are placed on the car, four-way guide posts mounted on the car adapted to receive adjacent corner portions of four adjacent compartments and two way guide posts at each 30 end of the car adapted to receive corner portions of two adjacent compartments; said side and end walls functioning as abutments for the containers.

2. In a railway car a frame comprising 35 side sills, end sills, center sills, needle beams and bolsters, end walls and side walls, substantially broad plates secured on top of the center sills, needle beams and bolsters, a reticulated flooring secured to the above 40 elements of the frame, two way guide posts secured to said floor at each end of the car, four way guide posts secured to said floor in line with the center sills at intermediate

points between the ends of the car in spaced pre-determined relation to each other, and 45 guideways secured to the inner face of the side walls in pre-determined spaced relation throughout the length of said side walls.

3. In a railway car a frame including side sills, center sills, end sills, needle beams and 50 bolsters, a reticulated floor secured to said above named elements, substantially wide bearing plates mounted on top of the center sills, needle beams and bolsters, supports secured above the end sills, side sills, center 55 sills, needle beams and bolsters, upon which laden compartments are adapted to rest, a two way guide post secured at each end of the car and four way guide posts secured at pre-determined intervals over the center sills 60 between the ends of the car and guides secured at pre-determined intervals to the inner face of the side walls of the car.

4. In a railway car a frame including side sills, center sills, end sills, needle beams and 65 bolsters, a reticulated floor secured to said above elements, substantially wide bearing plates mounted on top of center sills, needle beams and bolsters, supports secured above the end sills, side sills, center sills, needle 70 beams and bolsters upon which laden compartments are adapted to rest, a two way guide post secured at each end of the car and four way guide posts secured at pre-determined intervals over the center sills 75 between the ends of the car, and guides secured at pre-determined intervals to the inner face of the side walls of the car, and a reticulated flooring secured to the said sills and beams; said car being adapted to receive 80 and hold thereon against displacement a series of independently movable compartments adapted to hold lading.

In testimony whereof I affix my signature.

ALFRED H. SMITH.
